(57) **CLAIM**

The ornamental design for an air conditioner, as shown and described.

DESCRIPTION

FIG. 1. is a front perspective view of the front, right, and top sides of an air conditioner showing a first embodiment of our new design;

FIG. 2. is a front view thereof;

FIG. 3. is a rear view thereof;

FIG. 4. is a right side view thereof; a left side view being a mirror image thereof;

FIG. 5. is a top plan view thereof;

FIG. 6. is a bottom plan view thereof;

FIG. 7. is a front perspective view of the front, right, and top sides of an air conditioner showing a second embodiment of our new design;

FIG. 8. is a front view thereof;

FIG. 9. is a rear view thereof;

FIG. 10. is a right side view thereof; a left side view being a mirror image thereof;

FIG. 11. is a top plan view thereof;

FIG. 12. is a bottom plan view thereof;

FIG. 13. is a front perspective view of the front, right, and top sides of an air conditioner showing a third embodiment of our new design;

FIG. 14. is a front view thereof;

FIG. 15. is a rear view thereof;

FIG. 16. is a right side view thereof;

FIG. 17. is a left side view thereof;

(Continued)

FIG. 18. is a top plan view thereof;
 FIG. 19. is a bottom plan view thereof;
 FIG. 20. is a front perspective view of the front, right, and top sides of an air conditioner showing a fourth embodiment of our new design;
 FIG. 21. is a front view thereof;
 FIG. 22. is a rear view thereof;
 FIG. 23. is a right side view thereof; a left side view being a mirror image thereof;
 FIG. 24. is a top plan view thereof; and,
 FIG. 25. is a bottom plan view thereof.
